UNITED STATES PATENT OFFICE.

JOHN M. FORSYTH, OF LOS ANGELES, CALIFORNIA.

DESIGN FOR A SAFETY KNIFE-GUARD.

52,948.

Specification for Design.

Patented Feb. 4, 1919.

Application filed January 2, 1918. Serial No. 210,095. Term of patent 3½ years.

To all whom it may concern:

Be it known that I, JOHN M. FORSYTH, a citizen of the United States, residing at Los Angeles, in the county of Los Angeles and State of California, have invented a new, original, and ornamental Design for a Safety Knife-Guard, as shown, reference being had to the accompanying drawings, forming a part hereof.

In the drawings,—

Figure 1 is a side elevation of my design.

Fig. 2 is an end view thereof.

Fig. 3 is a perspective view of my design.

I claim,—

The ornamental design for a safety knife guard, as shown.

Signed at Los Angeles, in the county of Los Angeles, and State of California, this 6th day of April, 1917.

JOHN M. FORSYTH.
